UNITED STATES PATENT OFFICE

102,071

DESIGN FOR A VEHICULAR TANK

Frederick G. Thwaits, Wauwatosa, Wis., assignor to The Heil Co., Milwaukee, Wis., a corporation of Wisconsin

Application October 19, 1936, Serial No. 65,345

Term of patent 14 years

To all whom it may concern:

Be it known that I, Frederick G. Thwaits, a citizen of the United States, residing at Wauwatosa, in the county of Milwaukee and State of Wisconsin, have invented a new, original, and ornamental Design for a Vehicular Tank, of which the following is a description, reference being had to the accompanying drawing forming part thereof.

In the drawing:

Fig. 1 is a side elevation of a vehicular tank embodying my new design; and

Fig. 2 is a rear view of the vehicular tank.

The dominant or characteristic features of the new design are shown in solid lines.

I claim:

The ornamental design for a vehicular tank, substantially as shown and described.

FREDERICK G. THWAITS.
